UNITED STATES PATENT OFFICE.

JACOB ROBERTS, OF CATASAUQUA, PENNSYLVANIA.

MACHINE FOR MAKING HORSESHOES.

SPECIFICATION forming part of Letters Patent No. 501,298, dated July 11, 1893.

Application filed March 19, 1891. Serial No. 385,595. (No model.)

To all whom it may concern:

Be it known that I, JACOB ROBERTS, of Cata-
sauqua, Lehigh county, and State of Pennsyl-
5 vania, have invented a certain new and use-
ful Improvement in Machines for Making
Horseshoes, of which the following is a speci-
fication.

I will describe a machine embodying my
improvement and then point out the novel
10 features in a claim.

In the accompanying drawings, Figure 1 is
a back view of a machine embodying my im-
provement. Fig. 2 is a central vertical sec-
15 tion taken parallel with the side. Fig. 3 is a
vertical section of certain parts including the
dies. Fig. 4 is a view like Fig. 3, but repre-
senting parts in different positions. Fig. 5
is a top view of the bottom die. Fig. 6 is a
20 side view of the same die. Fig. 7 is a sec-
tion of this die at the plane of the dotted line
 $x x$ Fig. 5. Fig. 8 is a perspective view of a
horseshoe blank such as is to be submitted
25 to the action of the machine. Fig. 9 is a
horizontal section at the line $v v$ Fig. 8. Fig.
10 is a horizontal section at the line $w w$ Fig.
8. Fig. 11 is a perspective of the finished
horseshoe. Fig. 12 is a horizontal section at
25 the line $u u$ Fig. 11. Fig. 13 is a horizontal
section at the line $t t$ Fig. 11.

30 Similar letters of reference designate cor-
responding parts in all the figures.

A, B, designate two dies. A is the lower
die and B the upper die. As here shown, the
lower die A is fastened by means of a set
35 screw a in a recess formed in a reciprocating
table A'. This table is supported beneath
the die A by means of a shaft C. The shaft
C is free to derive rotary motion from the
reciprocating movement of the table. It de-
40 rives no rotary motion except from the table.
The journals of this shaft are sustained in
bearings c that are fitted to housings d in side
frames D. The side frames D are erected
upon a base piece E, and preferably united
45 therewith.

The rear end of the table A' works upon a
slideway consisting of a plate F erected upon
a standard F'. The latter may be fastened
to the base piece E. Preferably the table A'
50 will be engaged with the plate F by means of
clips a^2 embracing the side edges of the plate.
Pitman rods G are at one end pivotally con-

nected to the rear end portion of the table A'
and at the other end connected to crank pins
 $h^1 h^2$ carried by a shaft H. The crank pin h^1 55
extends from a crank arm h affixed to the
shaft H. The crank pin h^2 is affixed to a gear
wheel I that is affixed to the shaft H. Both
crank pins are in line and travel in unison.
As the shaft H rotates, it will reciprocate the 60
table and consequently the lower die A back
and forth. The shaft H is journaled in bear-
ings h^3 fitted to the housings of the side frames
D. The lower sections of these bearings are
supported by the upper sections of the bear- 65
ings c wherein the shaft C is journaled, springs
s being introduced between the top sections
of the bearings c and the lower sections of the
bearings h^3 . Screws J engaging with tapped
holes or nuts in the upper ends of the side 70
frames D and contacting with the top sections
of the bearings h^3 serve to adjust the latter
vertically so as to vary the position of the
shaft H relatively to the shaft C and table
A'. The screws J when adjusted may be re- 75
tained in position by inserting in plates P'
fastened to the top of the side frames D, pins
P, which will project across cranks formed on
or attached to the upper ends of said screws.

The rotary die B, as here shown, is fitted 80
in a holder b carried by the shaft H, and, as
here shown, formed integral with the latter.
A set screw b' serves to fasten this die in said
holder. As the shaft rotates, the die B is re-
volved, and its revolution is so timed rela- 85
tively to the reciprocation of the table A' that
this die will be opposite the lower die A, and
with it will press a horseshoe inserted be-
tween them. Preferably the shaft C will be
arranged with its axis a little in front of the 90
vertical plane in which the axis of the shaft
H is located. When so arranged, it will be
more certain to prevent the table from tilting.
The outer surface of the die B is rounded and
may be made concentric with the shaft H. 95

The lower die A is constructed to shape the
upper surface or top of a horse shoe. It has
a raised central portion a^5 of rounded or con-
vex form, and adjacent to this portion is pro-
vided with two clips $a^6 a^7$, whose opposite sur- 100
faces are arranged at the angle which the
heel portions of the shoe are to have and con-
verge upwardly, so that the space between
them is not only narrower toward the back of

the die, or, in other words, toward that part of the die which is the nearer to the back of the machine, but is also narrower at the upper part of the clips than at the bottom. The 5 main top surface of the die is inclined downwardly toward that portion where the heel of the shoe is formed, as may be best understood by reference to Fig. 6. The pressing surface of the upper die B is smooth. Owing to the 10 fact that the main top surface of the lower die A is inclined toward the heel or rear, the horseshoes when pressed by the dies will be thinner at the toe than at the heel. The crank pins h' h^2 are arranged at such a distance from the axis of the shaft H that the lower die A will have a slower surface speed than the upper die B. The lower die moves in the direction indicated by the arrow which is adjacent to the shaft H in Fig. 2, and hence the 15 pressing of the horseshoe will begin at the heel and continue toward the toe. The shoe embraces the central raised portion a^5 of the lower die A, and, consequently, as the pressing action of the upper die progresses from the heel 20 of a shoe toward the toe, the metal cannot be forced inward but is necessarily outward or toward the outer circumference of the shoe. By pressing in the described direction, and owing to the greater surface speed of the upper 25 die as compared with that of the lower die, I avoid carrying the wall of the shoe over at the toe, so as to close the crease or groove which is formed for the reception of the nail heads, and so giving too much under-cut, as 30 it is generally termed, an evil resulting very generally from pressing from toe to heel. The greater surface speed of the upper die tends 35 to move the metal rearward as the pressing progresses, although the pressing progresses from the heel to the toe of the shoe, and it is 40 due to this that the metal is not carried forward to increase the under-cut.

K designates ejectors for detaching each horseshoe, after the pressing operation, from

the lower die A. Two such ejectors will be 45 used. Only one is shown in Fig. 1 because it is desired to represent the dies. Each is supported upon an arm k extending from one of the side frames D toward the other of these side frames, and consists of a rod fitted to 50 slide in bearings k' with which said arm k is provided, and impelled toward the dies A, B, by means of a spring surrounding it and impinging at one end against one of the bearings k' and at the other end against a collar 55 k^2 which is fastened to the rod. When the lower die moves rearwardly the extremities of the heel of the horseshoe will strike the ejectors and be thus disengaged from the die. As the ejectors operate with a yielding action, 60 they will do their work without any injury. The wheel I engages with a wheel L affixed to a driving shaft M to which motion may be transmitted by a belt. Fixed and idler pulleys N' N^2 are mounted upon the shaft M and 65 the latter is also provided with a balance wheel O.

What I claim as my invention, and desire to secure by Letters Patent, is—

In a machine for pressing horseshoes, the 70 combination with driving mechanism, of a reciprocating table, a die thereon, having clips a^6 a^7 , a shaft, a die rotated by said shaft and coacting with the reciprocating die to press a shoe from heel to toe, cranks carried by the 75 shaft and connections between the cranks and table, the crank pins being arranged at such a distance from the axis of the shaft that the reciprocating die will have a slower surface speed than the upper die, substantially 80 as specified.

In testimony whereof I have signed my name to this specification in the presence of two subscribing witnesses.

JACOB ROBERTS.
